United States Patent Office.

MARCUS L. BATTLE, OF BAINBRIDGE, GEORGIA.

Letters Patent No. 99,050, dated January 25, 1870.

IMPROVED INSTRUMENT FOR PLUGGING TEETH.

The Schedule referred to in these Letters Patent and making part of the same.

To all whom it may concern:

Be it known that I, MARCUS L. BATTLE, of Bainbridge, in the county of Decatur, of the State of Georgia, have invented a new Instrument for Plugging Teeth with amalgam; and I do hereby declare that the following is a full and exact description thereof.

The nature of my invention consists in providing a steel instrument with three blades, for the purpose of filling teeth with amalgam.

Figure 1 is a top view;

Figure 2 is a side view; and

Figure 3, a bottom view, in which *a b c* represent the blades, *b b*, the concavities in two of the blades, and *c*, the plugger-point, passing through these concavities, when the side blades are closed.

To enable others skilled in the art to make and use my invention, I will proceed to describe its construction and operation.

This instrument, the "amalgam-carrier and plugger and combined," is made of steel, and has three blades, two of which are lateral, and one horizontal, fastened together by two rivets. One-fourth of each blade is made thin next to the handle, which gives each a spring. This spring is to keep the blades open. One-third of the end of the blade that forms the beak, is made tapering.

The lateral blades are curved at right angles at the point, and so grooved on the inside as to form a socket, when closed.

There is a pivot, which passes through the lateral blades, to keep them steady in position, when pressed together.

The horizontal blade is so tapered and curved at

the point, as to fit in the socket formed by the lateral blades.

There is a pivot passing down from the horizontal blade, between the lateral blades, which guides the plugger to the socket.

About one-fourth of the middle portion of the blades is file-cut, and also that portion of the handle which rests on the palm of the hand.

Teeth to be filled, should be properly prepared. A sufficient quantity of the amalgam should be thoroughly manipulated, and rolled in pellets smaller than the cavity to be filled, which are to be placed on the bracket, tray, or stand near by.

The instrument should be held in the right hand, resting the handle upon the palm, the lateral blades resting between the thumb and middle finger, with the forefinger resting on the horizontal blade or plugger. Then clasp the amalgam pellets with the beak of the lateral blades, and carry to the cavity, and, by the pressure of the forefinger upon the horizontal blade or plugger, the amalgam will be forced into the cavity. Repeat, until the filling is complete.

By this method, teeth can be filled with amalgam speedily, effectually, and with satisfaction to both operator and patient.

I claim an instrument for plugging teeth, composed of three blades, the two side blades furnished at the points with concavities, through which the plugger of the third blade passes, substantially as described.

MARCUS L. BATTLE.
